UNITED STATES PATENT OFFICE.

HUGO P. FREAR, OF BETHLEHEM, PENNSYLVANIA, ASSIGNOR TO BETHLEHEM SHIP-BUILDING CORPORATION, LTD., OF BETHLEHEM, PENNSYLVANIA, A CORPORATION OF DELAWARE.

BULK-CARGO CARRIER.

1,391,946.

Specification of Letters Patent. Patented Sept. 27, 1921.

Application filed April 15, 1920. Serial No. 374,074.

To all whom it may concern:

Be it known that I, HUGO P. FREAR, a citizen of the United States, residing at Bethlehem, county of Northampton, State of Pennsylvania, have invented a new and useful Bulk-Cargo Carrier, of which the following is a specification.

My invention relates to a novel construction of a vessel adapted for carrying ore or other dense bulk cargo confined by means of fore and aft trimming bulkheads, so that the ore cargo occupies a space running fore and aft but substantially less than the total width of the cargo hold, thereby increasing the stowage depth of the cargo. The effect of this is to elevate the ore or other dense bulk cargo so that its center of gravity will be approximately at the same height as the center of gravity of a cargo of ordinary density in a vessel of ordinary construction.

My invention further provides for bulk cargoes of ordinary density by utilizing the space not only between the trimming bulkheads above described but also the space on the outboard sides of the trimming bulkheads, hatches being arranged over the space between said trimming bulkheads above described for loading and discharging cargo whether carried in the space between the trimming bulkheads or in the space on the outer sides of the trimming bulkheads.

In order that the cargo may be loaded and discharged from the same central hatches, openings are provided at or near the top of the trimming bulkheads and at or about the level of the stowage top of ore or other dense cargo, thereby permitting an ordinary bulk cargo, after filling the space between the trimming bulkheads to overflow 40 through said openings into the wing spaces outboard of the trimming bulkheads.

To enable the cargo of ordinary density to be discharged through the central hatches, similar openings are provided at or near the bottom of the trimming bulkheads so that the cargo in the wing spaces can be transferred by hand or by mechanical means or preferably by gravity to the central space under the hatches.

To the above ends my invention therefore consists of a vessel of new and novel design adapted to carry an ore or other dense cargo which if carried in a vessel of ordinary design would require, for a full load, a relatively small percentage of the space obtaining in such vessels.

My invention, in its broad and generic scope, further comprehends a novel construction and arrangement of trimming bulkheads, with or without a novel arrangement of the inner skin of the vessel with reference to these trimming bulkheads.

By means of my invention, I am enabled to contract the cargo, thereby elevating it to the extent necessary for the following purposes:

(1.) Loading, trimming and discharging.
(2.) Distribution of the cargo.
(3.) Equally desirable metacentric heights (or degree of stability) with ore or other dense cargoes as with a cargo of average density properly stowed in a vessel of ordinary design.

(4.) Stowing the cargo in a contracted space and thereby reducing its liability to shift in a sea way.

(5.) To bring its center of gravity to approximately the same position as though the hold were of an ordinary design and loaded with a cargo of average density properly loaded, thereby reducing the tendency of the vessel to roll to excess with possible damage in a sea way and thereby further reducing the tendency of the cargo to shift.

(6.) Carrying ore or other dense cargo and providing means so that the wing spaces can be utilized together with the central space for carrying bulk cargoes of ordinary density when not carrying ore or other dense cargoes; the bulk cargoes of ordinary density being located and discharged through the same hatches as above described.

Other novel features of construction and advantage will hereinafter more clearly appear in the detailed description of my invention.

For the purpose of illustrating my invention, I have shown in the accompanying drawings embodiments thereof which are at present preferred by me, since such embodiments will be found in practice to give satisfactory and reliable results. It is, however, to be understood that the various instrumentalities of which my invention consists can be variously arranged and organized and that my invention is not limited to the precise arrangement and organization of these instrumentalities as herein shown and described.

Figure 1 represents a longitudinal, vertical, sectional, diagrammatic view of a novel

vessel, embodying my invention, arranged to carry ore or other dense cargo and also bulk cargoes of average density, certain of the parts being shown in elevation.

5 Fig. 2 represents a plan view looking down on deck showing more particularly the hatches, the bulkheads below the deck being shown dotted.

Figs. 3, 4, 5, 6, 7, 8, 9 and 10 represent, 10 respectively, cross sections illustrating various novel features and arrangements of the interior of the vessel. Figs. 11 and 12 represent cross sections showing more particularly the position a cargo of low specific 15 gravity assumes during the unloading operation.

Similar numerals of reference indicate corresponding parts.

Referring to the drawings,

20 The preferred arrangement of the propelling machinery and the navigating bridge is illustrated in Fig. 1 in which the propelling machinery is located aft and the navigating bridge forward, but it will be understood 25 that any other desired arrangement or location of machinery and bridge can be provided without departing from the spirit or scope of this invention.

1 designates my novel construction of 30 floating vessel and 2 designates the bottom of the hold. 3 designates double bottom compartments below the floor of the hold, 4 designates the cargo hold which includes both the central portion between the trimming bulkheads and also the space in the wings, outboard of the trimming bulkheads. 5 designates the hatches, it being apparent that modifications may be made in the sizes of the hatches and the intervals between said 40 hatches, depending upon the dimensions of the ship, characteristics of the cargo, and the loading and discharging methods and facilities, without departing from the spirit of this invention. 6 designates a hatch leading to a compartment or cargo hold forward of the limits of the dense cargo or other bulk cargo hold, but said hatch 6 may be entirely eliminated or increased or decreased in size in any particular case, according to 45 the dimensions and cargo carrying capacity of the vessel. 7 designates the trimming bulkheads arranged on either side of the center of the vessel but it will be apparent that their exact position will be governed by the density of the ore cargo, the arrangements shown providing for an ore cargo of 50 average density. 8 designates transverse diaphragms or bulkheads dividing the cargo hold into a number of compartments, but 55 it will be obvious that the space between said bulkheads may be increased or decreased, or the bulkheads may be omitted without departing from the spirit of this invention.

60 9 designates openings at or near the tops

of the trimming bulkheads to provide means for filling the wing spaces through the hatches after the middle space has been filled sufficiently for the cargo to overflow into the wings, it being apparent that said 70 openings may extend throughout the length of each portion of the hold between the bulkheads 8, or they may be provided at any desired intervals. 10 designates openings 75 below the bottom edges of the trimming bulkheads in order to permit the cargo in the wings to be trimmed toward the center, after the cargo in the central space has been discharged, thereby permitting the cargo from the wing compartments to be 80 discharged through the same hatch or hatches which are used for discharging the cargo carried in the central space.

Fig. 3 illustrates my invention in its simplest form wherein the floor of the hold 85 or the double bottom is carried straight across the vessel and the trimming bulkheads are shown in a vertical plane. With this arrangement, after the cargo is discharged from the central space, the cargo in the wing 90 spaces can be transferred to the center by hand or by mechanical means through the openings 10 to a position where it can be discharged through the hatches 5.

Fig. 4 shows another preferred arrangement of both the double bottom and the trimming bulkheads. The double bottom is sloped up outwardly in the manner shown at 11, so that the cargo in the wing spaces will trim by gravity to the central space 100 under the hatch, where it can be readily discharged in the same manner as the cargo in the central space is discharged. The trimming bulkheads are preferably provided with a flare at their tops and their bottoms 105 for reasons that anyone skilled in the art will readily understand.

Fig. 5 is the same as Fig. 4, except that the double bottom or what might preferably be called the inner skin is extended up to 110 the deck, as shown at 12.

Fig. 6 shows an arrangement similar to Fig. 5 except that the inner skin on each side of the vessel near the top is sloped upwardly and inwardly as at 13, meeting the 115 deck at the hatch coamings, or between the hatch coamings and the sides of the vessel.

Fig. 7 shows an arrangement which differs from Fig. 6 in that independent tanks 16 are formed, between portions of the inner skin 120 approximately parallel to the sides of the vessel and the outer skin, by diaphragms 14 and 15.

Fig. 8 shows a preferred arrangement desired for the particular density of the ore 125 cargo and the particular cargo of average density which it is desired to carry in the particular trade under consideration. The width of the hatches is approximately the same as the distance between the trimming 130

bulkheads. The upper and lower edges of the trimming bulkheads are flared outwardly. The inner skin shown in Fig. 7, disposed approximately parallel to the sides 5 of the vessel, is omitted. This is considered preferable where the greatest possible cubic capacity of the hold for cargoes of medium density is desired. The central portion of the double bottom 2 is shown at a lower level 10 than the inner edge of the sloping portion of the double bottom, which arrangement is preferred so that the cargo in the wing spaces in gravitating toward the center will accumulate in greater bulk and thus facilitate discharging by means of grab buckets or 15 other mechanical devices. The sloping sides of the interior skin under the deck are preferred in connection with the trimming bulkheads in order;—(a) to afford better means 20 for supporting the trimming bulkheads on a preferred arrangement of framing (not shown), (b) to render the cargo stowed in the wing spaces self trimming, and (c) to avoid voids in the hold which might permit 25 of the cargo shifting to a slight degree.

Fig. 9 shows the manner of loading and stowing an ore or other dense cargo in a vessel arranged as shown in Fig. 8. As the central space of the hold is filled in the manner shown, the ore or dense cargo arches 30 slightly at the openings 10 below, or at the lower openings of the trimming bulkheads, which arching together with the trimming bulkheads, retains the dense cargo in the 35 manner indicated, thereby raising the center of gravity sufficiently to insure easy rolling, minimum stresses and good sea-going characteristics.

Fig. 10 shows the manner of loading, trimming and stowing of a bulk cargo of average density in a vessel arranged as shown in Fig. 8. On the right hand side of the figure, the central space and the wing space is shown entirely filled by the cargo. The left hand 40 side of the figure shows the wing space partly filled and illustrates the cargo overflowing the tops of the trimming bulkhead 7 into the outer space. A void is indicated between the center of the vessel and the inboard side 45 of the trimming bulkheads on the left side of the figure in order to illustrate the manner in which the bulk cargo trims by gravity to the center of the vessel.

To one skilled in this art, it is obvious that 50 other arrangements as preferred may be adopted to meet special requirements without in any way departing from the broad and generic scope of my invention. Thus, depending upon the relation between the 55 specific gravities of the dense cargoes and the cargoes of average density, the trimming bulkheads may extend the full length of the hold in the manner illustrated in the preferred arrangement shown in Fig. 1, or the 60 trimming bulkheads may be omitted at either

end of the hold, or for a short distance amidships, or at any part of the hold; such portions of the hold in which the trimming bulkheads are omitted being intended primarily for the carrying of cargo of average density. 70

Figs. 1 to 10 inclusive are mainly diagrammatic and do not indicate any method or system of framing, as anyone skilled in the art can apply any of the well known systems of framing without departing from the spirit 75 or purpose of my invention. Any one of several systems of framing may be used for supporting and bracing the trimming bulkheads in an adequate and substantial manner. 80

In Fig. 4 a double bottom has its sides sloping upwardly and outwardly to the side walls of the vessel.

In Fig. 5 the inner skin slopes upwardly and outwardly toward the side walls of the 85 vessel and then extends upwardly to the deck preferably substantially parallel with the side walls of the vessel.

In Fig. 6 the inner skin slopes upwardly and outwardly from the double bottom toward the sides of the vessel, then extends upwardly a desired distance substantially 90 parallel with the sides of the vessel and then slopes inwardly, terminating in upward extensions which are connected with the deck 95 in proximity to the hatch coamings.

In Fig. 7 the construction is similar except that the upper and lower diaphragms are provided in order to form the independent tanks 16. 100

In Fig. 8 the inner skin slopes upwardly and outwardly from the depressed double bottom to the sides of the vessel, and other portions of the inner skin slope upwardly and inwardly from the side walls of the vessel and are secured to the deck in proximity to the hatch coamings. 105

It will be apparent that the space formed between the inner skin and the contiguous walls of the vessel may be employed as a 110 void space or as a stowage space for cargo, liquid cargo, for fuel, for liquid fuel or for water ballast.

In accordance with my present invention, I have devised a novel bulk cargo vessel 115 which is adapted to be employed in carrying a bulk cargo of relatively great density (e. g., ore), on a going trip, and without change of internal arrangements, a cargo of ordinary density, (e. g., coal) on the return 120 trip. It will be seen that when a cargo of relatively great density is carried, it will be retained in the central portion of the vessel between the trimming bulkheads (as shown in Fig. 9) thereby elevating the center of gravity above the position incident to a normal loading. In loading, a bulk cargo of ordinary density will overflow through opening 9 into the wing spaces after the 125 central space or spaces have been filled. 130

When such cargo of ordinary density is being discharged, the portions in the wing spaces will trim automatically by gravity (or may be trimmed by hand) to the center 5 space between the trimming bulkheads. In both cases, *i.e.*, for dense cargoes and cargoes of ordinary density, loading and discharging are effected through the same hatches.

In Fig. 11, I have illustrated diagrammatically the bulk cargo vessel in transverse section showing the vessel carrying a cargo of relatively low specific gravity, a portion of such bulk cargo having been removed.

In Fig. 12, I have shown more clearly the 10 manner in which the bulk cargo trims toward the center during the unloading operation.

It will be apparent, that in all the embodiments of my invention the trimming bulkheads 7, preferably stand upright or substantially vertical and that the height of said trimming bulkheads is in practice preferably less than the distance between the deck and the bottom of the hold or the inner 20 skin, or any such equivalent construction 25 may be employed whereby the top openings 9 and the bottom openings 10 are created for the purposes stated, although it will be apparent that the height of said trimming 30 bulkheads may be otherwise proportioned with respect to said distance, so long as said openings 9 and 10 are present for the purpose explained, it being essential that the 35 central cargo space and wing spaces outboard thereof, be intercommunicating at their tops and bottoms and that the bottoms of said wing spaces form continuations of the bottom of said central space, so as to 40 permit loading and unloading and to effect automatic trimming.

It will further be apparent that the upper and lower flaring terminals of the trimming bulkheads 7 seen in Figs. 4 to 12 inclusive serve to facilitate the automatic distribution or trimming of the cargo and in addition somewhat stiffen or strengthen said trimming bulkheads, as will be apparent to those skilled in this art.

It will be apparent that the flaring of 50 the trimming bulkheads has the additional special advantage in the loading and unloading of the cargo, since the means employed to effect the loading or unloading will readily clear from the bulkheads instead of catching thereon, as often occurs where the bulkhead terminals extend in the same plane or such as would otherwise occur in case the bulkheads were not flaring.

The present invention has been especially 60 designed for carrying a bulk cargo of ore on the trip in one direction and for carrying coal on the trip in the return direction, and in accordance with my present design, the vessel is able to carry the maximum cargo 65 in either direction without rendering it

necessary to render the ship stable by the introduction of water or other ballast, as is evident.

It will now be apparent that I have devised a novel and useful construction of a 70 bulk cargo carrier which embodies the features of advantage enumerated as desirable in the statement of the invention and the above description, and while I have, in the present instance, shown and described preferred embodiments thereof which will give in practice satisfactory and reliable results, it is to be understood that such embodiments are susceptible of modification in various particulars without departing from the 75 spirit or scope of the invention or sacrificing any of its advantages.

Having thus described my invention, what I claim as new and desire to secure by Letters Patent, is:

1. In a bulk cargo vessel of the character described, longitudinally extending, vertical trimming bulkheads on opposite sides of the center line extending in a fore and aft direction for any desired length of the hold, 80 the distance between said trimming bulkheads being substantially less than the width of the cargo hold, and the height of said bulkheads being less than the distance between the bottom of the hold and the 85 deck, whereby upper and lower openings are formed.

2. In a bulk cargo vessel of the character described, longitudinally extending, vertical trimming bulkheads on opposite sides of 90 the center line, extending in a fore and aft direction for any desired length of the hold, the distance between said trimming bulkheads being substantially less than the width of the cargo hold, there being openings in proximity to the top of said trimming bulkheads through which a cargo of 95 ordinary bulk will overflow into the side spaces after the center space or spaces have been filled, the height of said bulkheads being less than the distance between the bottom of the hold and the deck.

3. In a bulk cargo vessel of the character described, longitudinally extending, vertical trimming bulkheads on opposite sides of 100 the center line extending in a fore and aft direction for any desired length of the hold, the distance between said trimming bulkheads being substantially less than the width of the cargo hold, said trimming bulkheads 105 having openings in proximity to the bottom thereof, through which, after the cargo between the trimming bulkheads has been discharged through the hatches, the cargo in the side spaces may be trimmed to the center 110 for discharge through the same hatches, the height of said bulkheads being less than the distance between the bottom of the hold and the deck.

4. In a bulk cargo vessel of the character 115

- described, longitudinally extending, vertical trimming bulkheads on each side of the center line extending in a fore and aft direction for any desired length of the hold, 5 the distance between said trimming bulkheads being substantially less than the width of the cargo hold, there being openings in proximity to the top of said trimming bulkheads through which a cargo of ordinary bulk will overflow into the side spaces after the center space or spaces have been filled, and there being openings at or near the bottom of said trimming bulkheads through which, after the cargo between said 10 trimming bulkheads has been discharged through the hatches, the cargo in the side spaces may be trimmed to the center for discharge through the same hatches, the height of said bulkheads being less than the distance between the bottom of the hold and the deck. 15
5. A bulk cargo vessel having an inner skin, and upright trimming bulkheads extending in a fore and aft direction on opposite sides of the center line of the vessel, and there being trimming openings in proximity to the top of said trimming bulkheads, said inner skin having upper portions sloping toward said openings, and the height of said 20 bulkheads being less than the distance between the floor of said inner skin and the deck. 25
6. A bulk cargo vessel having an inner skin, and upright trimming bulkheads extending in a fore and aft direction on opposite sides of the center line of the vessel and there being trimming openings in proximity to the bottom of said trimming bulkheads, said inner skin having portions sloping toward said openings, and the height of said 30 bulkheads being less than the distance between the floor of said inner skin and the deck. 35
7. A bulk cargo vessel having an inner skin, and upright trimming bulkheads extending in a fore and aft direction on opposite sides of the center line of the vessel, there being upper and lower trimming openings in proximity to the top and bottom respectively of said trimming bulkheads, said inner skin having upper and lower portions sloping toward said upper and lower openings respectively, and the height of said bulkheads being less than the distance 40 between the deck and the floor of said inner skin. 45
8. A bulk cargo vessel having an inner skin, and upright trimming bulkheads extending in a fore and aft direction on opposite sides of the center line of the vessel, there being upper and lower trimming openings in proximity to the top and bottom respectively of said trimming bulkheads, said inner skin having upper and lower portions sloping toward said upper 50 and lower openings respectively, and the height of said bulkheads being less than the distance between the deck and the floor of said inner skin. 55
9. In a bulk cargo vessel of the character described, longitudinally extending, vertical trimming bulkheads of less height than the distance between the bottom of the hold and the deck, located on opposite sides of the center line extending in a fore and aft direction for any desired length of the hold, the distance between said trimming bulkheads being substantially less than the width of the cargo hold, and bulkheads extending transversely in the vessel to form a plurality of cargo receiving spaces. 60
10. In a bulk cargo vessel of the character described, longitudinally extending, vertical trimming bulkheads of less height than the distance between the bottom of the hold and the deck, located on opposite sides of the center line, extending in a fore and aft direction for any desired length of the hold, the distance between said trimming bulkheads being substantially less than the width of the cargo hold, there being openings in proximity to the top of said trimming bulkheads through which a cargo of ordinary bulk will overflow into the side spaces after the center space or spaces have been filled, said trimming bulkheads being flared outward at their upper portions. 65
11. In a bulk cargo vessel of the character described, longitudinally extending, vertical trimming bulkheads whose height is less than the distance between the bottom of the hold and the deck, located on opposite sides of the center line extending in a fore and aft direction for any desired length of the hold, the distance between said trimming bulkheads being substantially less than the width of the cargo hold, said trimming bulkheads having openings in proximity to the bottom thereof, through which, after the cargo between the trimming bulkheads has been discharged through the hatches, the cargo in the side spaces may be trimmed to the center for discharge through the same hatches, said trimming bulkheads being flared outward along their lower portions. 70
12. In a bulk cargo vessel of the character described, longitudinally extending, vertical trimming bulkheads whose height is less than the distance between the bottom of the hold and the deck, located on each side of the center line extending in a fore and aft direction for any desired length of the hold, the distance between said trimming bulkheads being substantially less than the width of the cargo hold, there being openings in proximity to the top of said trimming bulkheads through which a cargo of ordinary bulk will overflow into the side spaces after the center space or spaces have been filled. 75

- and there being openings at or near the bottom of said trimming bulkheads through which, after the cargo between said trimming bulkheads has been discharged through 5 the hatches, the cargo in the side spaces may be trimmed to the center for discharge through the same hatches, said trimming bulkheads being flared outward at their upper and lower portions.
- 10 13. A bulk cargo vessel of the character described, having an inner skin and having in its cargo receiving space longitudinally extending, vertical trimming bulkheads whose height is less than the distance between 15 said inner skin and the deck, spaced from each other to elevate and retain a cargo of relatively great density, there being upper and lower trimming openings in proximity to the top and bottom of said trimming bulkheads, said upper trimming openings effecting the automatic trimming of a cargo of ordinary density into the wing spaces outboard of said bulkheads when loading, portions of said inner skin sloping toward said lower openings, said sloping portions of said inner skin contributing with said lower trimming openings to effect automatic trimming of said cargo of ordinary density into the spaces inboard of 20 said bulkheads when unloading.
14. A bulk cargo vessel of the character described, having in its cargo receiving space longitudinally extending, vertical trimming bulkheads, spaced from each other to elevate and retain a cargo of relatively great 25 density, there being upper and lower trimming openings in proximity to the top and bottom of said trimming bulkheads, said upper trimming openings effecting the automatic trimming of a cargo of ordinary density into the wing spaces outboard of said bulkheads when loading, and said lower trimming openings permitting the trimming of said cargo of ordinary density into the 30 space inboard of said trimming bulkheads when unloading.
15. A bulk cargo vessel having an inner skin, a portion of which on either side of the center line is substantially horizontal, other portions of said skin being sloped upwardly and outwardly toward the sides of the vessel, other portions of said inner skin being carried upwardly to the deck substantially parallel to the side walls of the 35 vessel, vertical trimming bulkheads whose height is less than the distance between said skin and the deck disposed on opposite sides of the center line and extending in a fore and aft direction for any desired length of the hold, the distance between said trimming bulkheads being substantially less than the width of the cargo hold.
- 40 16. A bulk cargo vessel having an inner skin, a portion of which at its bottom on opposite sides of the center line is substan-
- tially horizontal, other portions of said inner skin sloping upwardly and outwardly toward the sides of the vessel, then extending upwardly and then sloping inwardly and upwardly to meet the deck in proximity to the hatch coamings, vertical trimming bulkheads whose height is less than the distance between said skin and the deck disposed on opposite sides of the center line and extending in a fore and aft direction for any desired length of the hold, the distance between said trimming bulkheads being substantially less than the width of the cargo hold. 70
17. A bulk cargo vessel having an inner skin, a portion of which forms a double bottom on opposite sides of the center line, then sloping upwardly and outwardly toward the side of the vessel, then substantially vertically or parallel to the sides of the vessel, and terminating in inwardly and upwardly sloping portions meeting the deck in proximity to the hatch coamings, fore and aft water tight diaphragms extending laterally from the upper and lower edges of the substantially vertically extending portion to the adjacent sides of the vessel, and vertical trimming bulkheads whose height is less than the distance between said skin and the deck on opposite sides of the center line extending in a fore and aft direction for any desired length of the hold, the distance between said bulkheads being substantially less than the width of the cargo hold. 80
18. A bulk cargo vessel having an inner skin, the lower portion of which forms a substantially horizontal double bottom on either side of the center line, then slopes upwardly and outwardly toward the sides of the vessel, other portions of said skin extending downwardly and outwardly from the deck in proximity to the hatch coamings to the adjacent sides of the vessel, fore and aft water-tight diaphragms extending laterally from the lower edges of the said upper sloping portions to the adjacent sides of the vessel, and upright trimming bulkheads whose height is less than the distance between said skin and the deck disposed on opposite sides of the center line and extending longitudinally in a fore and aft direction for any desired length of the hold, the distance between said bulkheads being substantially less than the width of the cargo hold. 90
19. A bulk cargo vessel having an inner skin forming a false bottom, the inner skin above said false bottom sloping outwardly toward the sides of the vessel to bring the bottom at a lower level than the inner edges or sloping portions of said inner skin, and vertical trimming bulkheads extending longitudinally in a fore and aft direction for a desired length of the hold on opposite sides 100
- 110
- 120
- 125
- 130

- of its center line, the space between said bulkheads being substantially less than the width of the cargo hold, and the height of said bulkheads being less than the distance 5 between said bottom and the deck.
20. In a bulk cargo vessel of the character described, longitudinally extending, vertical trimming bulkheads whose height is less than the distance between the bottom of the 10 hold and the deck, located on opposite sides of the center line extending in a fore and aft direction for any desired length of the hold, said trimming bulkheads being so located that they will confine and retain an ore or 15 other dense cargo in a space substantially less than the width of the cargo hold, thereby elevating the center of gravity of the cargo and facilitating loading, trimming and discharging the cargo, and at the same time 20 safeguarding the cargo against shifting in a seaway.
21. In a bulk cargo vessel of the character described, longitudinally extending, vertical trimming bulkheads whose height is less than the distance between the bottom of the 25 hold and the deck, located on opposite sides of the center line, extending in a fore and aft direction for any desired length of the hold, the distance between said trimming 30 bulkheads being substantially less than the width of the cargo hold, said bulkheads contributing with adjacent walls of the vessel to form openings at or near the top of said trimming bulkheads through which a cargo 35 of ordinary bulk will overflow into the side spaces after the center space or spaces have been filled.
22. In a bulk cargo vessel of the character described, longitudinally extending, vertical 40 trimming bulkheads whose height is less than the distance between the bottom of the hold and the deck, located on opposite sides of the center line extending in a fore and aft direction for any desired length of the 45 hold, the transverse distance between said trimming bulkheads being substantially less than the width of the cargo hold, said trimming bulkheads contributing to form openings at or near the bottom thereof, through 50 which, after the cargo between the trimming bulkheads has been discharged through the hatches, the cargo in the side spaces may be trimmed to the center for discharge through the same hatches.
23. In a bulk cargo vessel of the character 55 described, longitudinally extending, vertical trimming bulkheads on each side of the center line extending in a fore and aft direction for any desired length of the hold, the transverse distance between said trimming bulkheads being substantially less than the width 60 of the cargo hold, an inner skin, there being openings at or near the top of said trimming bulkheads through which a cargo of ordinary 65 bulk will overflow into the side spaces after the center space or spaces have been filled and there being openings at or near the bottom of said trimming bulkheads through which, after the cargo between the said trimming bulkheads has been discharged through the hatches, the cargo in the side spaces may be trimmed to the center for discharge 70 through the same hatches.
24. In a bulk cargo vessel of the character described, a floor or a double bottom 75 across the vessel, the space below said floor or said double bottom being adapted for use:—as void space, or as stowage space for cargo, for fuel, for liquid cargo, for liquid fuel, or for water ballast, longitudinally extending, vertical trimming bulkheads whose 80 height is less than the distance between said floor and the deck located on opposite sides of the center line extending in a fore and aft direction for any desired length of the 85 hold, the transverse distance between said trimming bulkheads being substantially less than the width of the cargo hold, there being openings at or near the top of said trimming bulkheads through which a cargo of 90 ordinary bulk will overflow into the side spaces after the center space or spaces have been filled and there being openings at or near the bottom of said trimming bulkheads through which, after the cargo between 95 said trimming bulkheads has been discharged through the hatches, the cargo in the side spaces may be trimmed to the center for discharge through the same hatches.
25. In a bulk cargo vessel of the character 100 described, an inner skin forming a floor or a double bottom across the vessel, substantially horizontal on either side of the center line, said inner skin contiguous to said horizontal portion sloping upwardly 105 and outwardly to the sides of the vessel, the space below said floor or said double bottom being adapted for one or more of the following uses:—as a void space, or as stowage space for cargo, for fuel, for liquid 110 cargo, for liquid fuel, or for water ballast, longitudinally extending, vertical trimming bulkheads on opposite sides of the center line extending in a fore and aft direction 115 for any desired length of the hold, the distance between said trimming bulkheads being substantially less than the width of the cargo hold, there being openings at or near the top of said trimming bulkheads through which a cargo of ordinary bulk will overflow into the side spaces after the center space or spaces have been filled and there being openings at or near the bottom of said trimming bulkheads through which, after the cargo between the said trimming bulkheads has been discharged through the hatches, the cargo in the side spaces will 120 trim by gravity to the center for discharge 125.

through the same hatches, and said trimming by gravity being facilitated by the said sloping portions of said inner skin.

26. In a floating vessel of the character described, longitudinally extending, substantially vertical, trimming bulkheads located on opposite sides of the center line and extending in substantial parallelism in a fore and aft direction, the height of said bulkheads being less than the distance between the bottom of the hold and the deck, whereby upper and lower openings are formed, and the distance between said trimming bulkheads being less than the width of said hold.

27. In a floating vessel of the character described, an inner skin having its outer portions sloped upwardly, and longitudinally extending, substantially vertical, trimming bulkheads located on opposite sides of the center line, the height of said bulkheads being less than the distance between said skin and the deck, the upper and lower portions of said bulkheads being flared outwardly, and the distance between said bulkheads being less than the width of the cargo hold.

28. In a floating vessel of the character described, longitudinally extending, vertical, trimming bulkheads located on opposite sides of the center line and extending in substantial parallelism in a fore and aft direction, an inner skin, the height of said trimming bulkheads being less than the distance between said skin and the deck and said trimming bulkheads being flared outwardly at their upper and lower portions, and transverse bulkheads whose height is substantially co-extensive with the distance between said skin and deck.

29. In a floating vessel of the character described, longitudinally extending, vertical, trimming bulkheads located on opposite sides of the center line, the height of said bulkheads being less than the distance between the bottom of the hold and the deck, said bulkheads being flared outwardly at their upper and lower portions, and transverse bulkheads, whose height is substantially co-extensive with the distance between the bottom of said hold and the deck, for forming a plurality of cargo receiving spaces.

30. In a floating vessel of the character described, longitudinally extending, substantially vertical, trimming bulkheads, located on opposite sides of the center line and extending fore and aft, the distance between said bulkheads, being less than the width of the cargo hold, and the height of said bulkheads being less than the distance between the deck and the bottom of the hold, whereby upper and lower openings are formed and transverse bulkheads whose height is greater than said trimming bulk-

heads whereby independent cargo receiving spaces are formed.

31. A floating vessel of the character described, provided with a cargo hold having a central space and wing spaces outboard thereof, upright trimming bulkheads intermediate said spaces, the latter being in communication at their tops and bottoms and the bottoms of said wing spaces forming continuations of the bottom of said central space.

32. A floating vessel of the character described provided with a cargo hold having a central space and wing spaces outboard thereof, upright trimming bulkheads intermediate said spaces which are intercommunicating at their upper portions and said wing spaces being in free communication with said central space at substantially its greatest depth.

33. In a floating vessel of the character described, longitudinally extending upright trimming bulkheads dividing the cargo holds into a central hold and two side holds, said holds communicating at their tops and bottoms and said bulkheads being spaced to insure a proper degree of stability, when the central hold is fully loaded with a bulk cargo of a particular density.

34. In a floating vessel of the character described, longitudinally extending, vertical trimming bulkheads dividing the cargo holds into a central hold and two side holds intercommunicating at their tops and bottoms, said bulkheads being spaced to insure a proper degree of stability, when the central hold is fully loaded with a bulk cargo of a particular density, and to insure substantially the same degree of stability when the central and side cargo holds are fully loaded with another bulk cargo of a particular density less than the density of said first mentioned bulk cargo.

35. In a bulk cargo carrier, trimming bulkheads flaring at their upper and lower portions and contributing with the juxtaposed walls to form trimming openings at their top and bottom.

36. In a bulk cargo carrier, trimming bulkheads contributing to form a central cargo space and wing spaces outboard thereof, intercommunicating at their tops and bottoms, the bulkheads being so spaced as to give the vessel the same stability when the central cargo space is fully loaded with a cargo of one density as when the central and wing spaces are fully loaded with a cargo of a materially less density than the density of the first cargo, without rendering it necessary to employ ballast to insure the stability of the vessel.
